UNITED STATES PATENT OFFICE.

JULIUS MUGLER, OF BERLIN, AND HERMANN WÖLKE, OF BREMEN, GERMANY.

STEAM-POWER PLANT FOR SUBMARINE BOATS.

Original application filed December 3, 1921, Serial No. 519,607. Patent No. 1,511,902, dated October 14, 1924. Divided and this application filed September 27, 1924. Serial No. 740,379.

To all whom it may concern:

Be it known that we, JULIUS MUGLER and HERMANN WÖLKE, citizens of Germany, residing at Berlin, Germany, and Bremen, Germany, respectively, have invented certain new and useful Improvements in Steam-Power Plants for Submarine Boats, of which the following is a specification.

This invention is for a submarine boat, and relates particularly to the construction and disposal of a steam power unit therefor, and is a division of our copending application Serial No. 519,607, filed December 3, 1921, now issued as Patent No. 1,511,902, dated October 14, 1924.

The higher speeds obtainable from steam operated power plants for submarines over the more common internal combustion engine type of power unit is recognized by those skilled in the art. However, considerable difficulty is encountered in the disposition of the steam generators so as not to necessitate an increase in the overall length of the craft, or so as not to require additional room needed for other purposes. Another source of difficulty is the insulation of heat and the protection of the crew from the effects of heat radiating or conducted from the generators.

The present invention has for its principal objects to provide a power unit in a submarine vessel having a storage capacity for the conservation of steam for use in underwater cruising.

Another important object of the invention is to provide a novel arrangement of the steam generators with respect to the construction of the boat so as to reduce the interior space of the vessel occupied by the steam generators to a minimum, so that very little useful space is required for them, without reducing their size to a point where they are inefficient or uneconomical.

These and other objects and advantages are attained by my invention, which is illustrated in the accompanying drawings, all of which are diagrammatic views. In the drawings:

Fig. 1 is a transverse section through a submarine hull, but showing an end view of the high pressure generators and storage units;

Fig. 2 represents a longitudinal view through a portion of the ship's hull, show-

ing the arrangement of the generators, the 55 dotted line representation indicating the removability of the generators from the housings in which they are contained;

Fig. 3 is an enlarged view illustrating a longitudinal section through one of the high 60 pressure boilers; and

Fig. 4 is a front view thereof, showing a portion of the front broken away.

In the drawings, 5 designates the outer shell of a submarine boat of accepted design, within which is the inner or pressure resisting hull 6, the latter being in spaced relation to the former, as explained in our patent above referred to.

Intermediate the ends of the boat, preferably amidships thereof, are steam generator or boiler rooms or compartments 7, which are between the inner and outer hulls, the rooms projecting laterally from the inner or pressure resisting hull. It is generally preferable to so shape the inner hull that the wall along the inside of the generator room will bulge or bow inwardly, as indicated at 8, thus occupying some of the space within the interior of the hull. In 80 each generator room are one or more boilers 7a.

For generating steam for surface cruising, and for storing it for underwater cruising, special high pressure generators are employed. The generators, designated 7a, are enclosed in a casing 13 surrounded by a second shell 14 which is spaced from the inner shell. Spaced outside this shell, is a casing 15 that may be common, in part, to the inner hull 6 of the vessel. The space 16 between shells 14 and 15 is preferably evacuated to provide heat insulation.

The space 17 between shells 13 and 14 is a steam chamber which communicates with the steam generator 7 through a pipe 18 in which is a manually operable valve 19. Inasmuch as the steam reservoirs or conservors immediately surround the steam generator, they are kept hot by the excess heat from the generator. To further heat the space, a baffle 20 may be placed in the flues 21 for directing the hot gases of combustion through U-shaped tubes 22 disposed in the space 17, and having their opposite ends opening into the flue on opposite sides of the baffle.

In the event that the space 17 is not suffi-

cient, and to increase the underwater cruising range, space 17^a, see Figs. 2 and 4, at the end of the generator may be utilized for steam storage.

5. In operation, where steam is used for underwater cruising, the steam flows through pipe 18 back into the generators, where it passes through the usual conduits, such as pipe 23, to the turbines. This simplifies the 10 necessary arrangement of pipes and valves, and simplifies the operation when making a changeover.

The compartments for the high pressure generators are spaced apart longitudinally, 15 as shown in Fig. 2. The high pressure generator units may be provided with removable end plates 24, so that, when necessary, the generator can be removed from the inner shell when the end plate is removed, 20 and brought into the space between the two generators, as shown in dotted lines in Fig. 2, for repairs.

Any preferred type of boiler, *per se*, may 25 be used. We have illustrated a water tube boiler having cylindrical compartments 25 and water tubes 26.

Oil is preferably used as a fuel, and in 30 Fig. 4, 27 designates the ends of suitable oil burners.

30. The drawings are to be considered merely as illustrative of the invention, and various details of construction and arrangement may be modified within the contemplation of the invention and under the scope of the 35 appended claims.

We claim as our invention:

1. A steam power plant for submarines, comprising a high pressure water tube steam boiler for surface cruising, surrounded by 40 a steam receiver for underwater cruising,

insulating means surrounding the receiver, said receiver having pressure resisting walls 45 separate from those of the boiler, and a controllable communication between the boiler and the receiver.

2. A steam power plant for submarines comprising a high pressure water tube steam boiler for surface cruising, surrounded by a high pressure steam receiver for underwater 50 cruising, heat insulating means surrounding the receiver, a controllable communication between the boiler and the receiver, a connection to the boiler by means of which steam is drawn from the boiler and the receiver, tubes in said receiver through which the furnace gases are passed, and means for directing furnace gases from the boiler through the tubes.

3. A submarine boat having a steam power plant including a high pressure generator, 60 a high pressure steam receiver surrounding the generator having pressure resisting walls separate from those of the boiler, a controllable communication between the boiler and receiver, a flue, and passages in 65 the receiver through which gases of combustion pass from the boiler to the flue.

4. A power plant comprising a double walled cylindrical casing between the walls of which is a steam chamber, a water tube 70 boiler removably received within the casing, a pipe connecting the boiler and shell having a valve therein, and a removable end plate detachably secured at one end of the shell and entirely separate therefrom, to 75 permit removal of the generator.

In testimony whereof we affix our signatures.

JULIUS MUGLER.
HERMANN WÖLKE,
